FABRIC TESTING MACHINE

Arno Paul Nonweiler, Oshkosh, Wis., assignor to
 A. P. Nonweiler Company, Oshkosh, Wis., a
 corporation of Wisconsin

Application August 11, 1933, Serial No. 684,640

8 Claims. (Cl. 265—14)

This invention relates to improvements in the art of testing fabrics.

In the construction of airplanes it is common practice to treat the fabric used with a liquid,

5 commonly termed "dope". This dope serves to protect the fabric from the elements and to cause a shrinking or tautening thereof. A plurality of coats is usually applied and the degree of tautness obtained depends partly upon the number of 10 said coats, partly upon the composition of the dope, and partly upon a number of other factors such as type of fabric, temperature, humidity, time interval between coats, and method of application. Heretofore, the final result obtained 15 by treatment of fabric has been largely a matter of guess-work. This is necessarily objectionable as the efficiency of the airplane and the safety of the passengers may depend upon the manner in which the fabric is treated and this treatment 20 should be such that the fabric offers a surface which is semi-rigid to a predetermined degree to form a constant air foil. Heretofore, various devices have been developed for testing the tensile strength of the fabrics by recording the resistance 25 to stretching action. None of these devices, however, is capable of solving the present problem wherein the dimensional changes of fabric under shrinkage and the shrinkage forces are studied.

It is therefore one of the objects of the present invention to provide an improved fabric testing device which makes it possible to obtain an accurate record of the behavior of dope and fabric when the dope has been applied to the latter, thus enabling the manufacturer of dope to place accurate laboratory control on the manufacture, and enabling the buyer of material to purchase by specification in terms of resistance to pressure developed by shrinkage of the cloth in pounds per square foot.

40 A further object of the invention is to provide a device as above described wherein a record is obtained of the shrinkage forces not only as they act in one direction on the fabric but in all directions, said record being obtained without changing the position of the fabric and without disturbing the top surface by depression or distortion, thus making it possible to apply additional coats of dope while the test is being made so that a study of the effect of time interval between 45 coats may also be made.

A more specific object of the invention is to provide a fabric testing device in which a hydraulic medium is utilized in transmitting pressure forces to a suitable gauge or recording device.

50 55 A further object of the invention is to provide

a fabric testing device constructed to measure linear dimensional changes in the fabric as well as the resistance to pressure developed by shrinkage of the cloth in pounds per square foot.

A further object of the invention is to provide 5 an improved device which makes it possible to study the effect of the application of dope or other liquid upon fabric.

A further object of the invention is to provide an improved fabric testing device, which, while 10 particularly adapted for use in the aeronautical field, may be employed in connection with the study of the behavior of various types of fabrics under various conditions or treatments.

With the above and other objects in view the invention consists of improvements in the art of 15 testing fabrics, and all its parts and combinations as set forth in the claims, and all equivalents thereof.

In the accompanying drawings illustrating one 20 complete embodiment of the preferred form of the invention in which the same reference numerals designate the same parts in all of the views:

Fig. 1 is a central longitudinal vertical sectional view through the device;

Fig. 2 is an enlarged detail sectional view taken 25 on line 2—2 of Fig. 1;

Fig. 3 is a plan view in perspective of the device; and

Fig. 4 is an enlarged plan view of a portion of 30 the device showing a piece of fabric in testing position.

Referring more particularly to the drawings, the numeral 5 designates a suitable base which has mounted preferably near one end thereof a 35 cylinder or tank 6, said cylinder having its upper end provided with an air valve 7 and having a valve 8 associated with its lower end and controlling the flow of hydraulic medium from the tank to a tube 9 communicating with a conduit 10.

A short section of tubing 11 extending from the conduit 10 communicates with a jacket 12 surrounding the lower end of the mercury tube 13 of a thermometer 14.

45 Another short section of tubing 15 extending from the conduit 10 communicates with a pressure gauge 16 of any standard construction.

Another section of tubing 17 extending from the conduit 10 communicates with a central vertical port 18 of a cross-connector 19. A relief valve 20 is associated with the upper end of the duct 18. The cross-connector 19 has four externally threaded extensions 21 the ends of which are recessed as at 22 to form chambers. Four 50 55

lower ducts 23 extend from the central duct 18 to the chambers 22 and four upper ducts 24 connect in a similar manner. A flexible membrane or disc 25, preferably of rubber, is secured over the ends of the extensions 21. Four cylinders 26 having annular shoulders 27 formed on their inner ends are held in alignment with the extensions 21 against the membranes 25 by means of nuts 28.

10 Within each cylinder 26 is a slideable piston 29 having a slotted outer end 30 within which the inner end of a connecting rod 31 is held by means of a pin 32.

Four lever members 33 preferably triangular shaped, are pivoted on rods 34 mounted in blocks 35 on the base. The outer ends of the rods 31 are pivoted as at 36 in the slotted ends of bolts 37 extending through the levers 33.

The upper end of each lever 33 carries a horizontally extending threaded adjusting rod 38 which is adapted to be operated by means of a nut 39. The inner ends of the adjusting rods extend through the upper ends of the levers and have clevices 40 associated therewith for vertical pivoting movement.

One of the levers 33 has pivoted near the lower end thereof one end of a rod 41 and the other end of said rod extends slidably through a sleeve 42 associated with the lower portion of the lever 33 directly opposite. A clamp 44 secured to said sleeve 42 supports a gauge 45 having an operating button 46. This gauge is preferably of the "Starrett" type and is adapted to measure distance of travel or movement. It is operated by pressure of the outer end of the rod 41 upon the button 46. The other two lever members 33 are connected by a similar rod 41 operating a similar gauge 45 as shown in Fig. 3.

The conduit 10 which extends below the base member 5 may be enclosed in a pan 46, said pan being adapted to hold water or other liquid for controlling the temperature of the hydraulic medium in the conduit 10.

In use of the device it is preferred to employ a section of fabric 47 preferably one foot square and having the corners notched out as at 48. Each side edge of the fabric is folded over and hemmed to form a tube 49 for receiving a bar 50. The bars 50 are then inserted in the clevices 40 and held in position by means of pins 51.

Airplane dope is a substance used as a protective coating and also as a means of shrinking and thereby tautening the fabric to such a point that it offers to the wind a semi-rigid surface to form a constant air foil. This dope usually consists of a solid, a solvent, a diluent and a plasticizer. The solid may be nitro cellulose and is adapted to form a film on the fabric and behave like a jell of the reversible type that swells as a result of the solvents and then shrinks as the solvent evaporates. It is well-known that the type, character, and rate of evaporation of the solvent materially affects and controls the degree of tautening when the material is applied to a fabric. The purpose of the present instrument is to give a more comprehensive method of studying the behavior of the dope. It is well known that when the fabric is wet with the first coat of dope it causes a general loosening of the entire fabric. The succeeding coats, however, tauten the fabric as desired and the present instrument makes it possible to determine how many coats are desirable to obtain a predetermined degree of tautening. It also makes it pos-

sible to determine the effect of various types of solvents in the dope and the amount thereof, to determine the effect on the particular type of fabric treated and to determine the effect of temperature, humidity and time interval between coats. It also makes it possible to determine the effect of varying the amount or type of other ingredients besides the solvent in the dope.

With the fabric in position as shown in Fig. 4 the adjusting nuts 39 are manipulated to take up the fabric somewhat and next, with a suitable hydraulic medium partially filling the tank 6 and filling the system, air under pressure is forced into the tank 6 through the air valve 7, the valve 8 being closed. When a desired pressure has been built up within the tank the valve 8 is opened thereby creating a pressure within the system which pressure is communicated to the rubber membranes 25 due to the fact that the hydraulic medium flows through the ducts 18, 23 and 24 into the chambers 22. The valve 8 is kept open long enough to build up a desired starting pressure indicated by the pressure gauge 16 and for purposes of example we may assume that twenty pounds on the gauge is a suitable starting reading.

When the first coat of dope is applied to the testing piece 47 of fabric it will at first, as before mentioned, cause a general loosening which may cause the gauge 16 to drop back to 15. When a second coat of dope is applied after the first coat has dried, shrinkage will begin and the fabric will therefore tend to exert an inward pull on the upper ends of the levers 33. This will cause an inward movement of the inner ends of the rods 31 and through the pistons 29 and rubber membranes 25 will exert a back pressure on the hydraulic medium in the system which will increase the pressure shown on the gauge and the gauge will then, for purposes of example, move back to twenty pounds. After the second coat is dried a third coat may be applied which will cause still further shrinkage and which may increase the reading on the gauge to thirty. A fourth coating will cause additional shrinkage and may cause the gauge to rise to sixty. Inasmuch as the gauge 45 employed has a ratio of four to one, the final result will be one-fourth of sixty or fifteen, showing that the dope has acted on the fabric to exert a force of fifteen pounds per square foot.

While the shrinkage is taking place there will also be a movement of the lower rods 41 which will cause operation of the gauges 45 and these gauges, as before mentioned, indicate the distance of travel or amount of movement of the fabric during the shrinking process. These auxiliary gauges 45 in addition to showing the amount of movement, serve as a check upon the pressure gauge, as by use of the device it will be found that a certain reading in the gauge 16 should result in a predetermined reading in the gauges 45. If these gauges do not suitably check up, it may be assumed that there is a leak in the hydraulic system.

An important feature of the present invention resides in the use of the four lever members each pair of which acts at right angles to the other pair. With this arrangement the shrinkage in all directions will be accurately indicated simultaneously and through a common means, eliminating the necessity of shifting the fabric to obtain readings in both directions. This therefore makes it possible to apply one coat of dope after another without in any way disturbing the fabric on the device and to thereby study all of the 75

effects of variation in the composition of the dope, of temperature, humidity, method of application and type of fabric with relation to tautening of the fabric.

5 The device therefore makes it possible for the manufacturer of dope to place accurate laboratory control on the manufacture thereof to produce a specified result in the fabric and also permits the buyer of the fabric which has been treated to purchase on a specification basis. Thus different requirements of different users in connection with the degree of tautness of the fabric may be easily taken care of in an accurate manner.

10 The expression "means responsive to movement of the levers" as used in the claims refers to the mechanism associated with the levers for creating pressure in the hydraulic system to operate the gauge 16. The term "lateral pressure" as used in the claims is any pressure against a side 15 of the fabric such as the fabric is subjected to during use in aeroplanes. The resistability of the fabric to lateral pressure depends upon the tautness developed as a result of the shrinkage 20 and therefore a study of the effect of the shrinkage 25 in producing various degrees of tautness gives a study of the resistability of the fabric to lateral pressure.

20 Although only one form of the invention has been shown and described it is obvious that various changes may be made therein and that the invention may be utilized in other adaptations, and all such changes are contemplated as may come within the scope of the claims.

30 What I claim is:

35 1. A device for studying the shrinkage of fabric under particular conditions comprising four spaced members adapted for readily and detachably supporting a section of fabric from four sides, said members being movable by the fabric when a 40 change in characteristic of the fabric occurs, and means actuated by said supporting members when so moved for simultaneously indicating the behavior of the fabric in a plurality of directions.

45 2. A device for studying the shrinkage of fabric comprising four spaced members adapted for readily and detachably supporting a section of fabric from four sides, said members being movable by shrinkage of the fabric, and means actuated by said supporting members when so moved 50 for indicating the resistance of said fabric to shrinkage force per unit area.

55 3. A device for studying the shrinkage of fabric comprising four spaced members adapted for readily and detachably supporting a section of fabric from four sides, said members being movable by shrinkage of the fabric, and hydraulic means actuated by said supporting members when so moved for indicating the resistance of said fabric to shrinkage force per unit area.

60 4. A device for studying the shrinkage of fabric

comprising opposed pivotally mounted levers, means for supporting a section of fabric between said levers, and hydraulically actuated means responsive to movement of the levers as a result of a change in characteristic of said fabric for 5 indicating the behavior of said fabric under particular conditions.

5 5. A device for studying the characteristics of fabric comprising opposed pivotally mounted levers, means for supporting a section of fabric 10 between said levers, a housing having a chamber therein, hydraulic medium within said chamber, a hydraulically operated pressure gauge communicating with said chamber, oppositely positioned cylinders associated with said housing, 15 pistons movable in said cylinders, resilient means separating said chamber from said cylinders, and means connecting said pistons to said levers for transmitting movement of said levers caused by a change in characteristic of the fabric to said pistons to thereby cause a change in the pressure 20 condition of said hydraulic medium.

6. A device for studying the characteristics of fabric, comprising four pivotally mounted levers having means in connection therewith constructed 25 and positioned to support fabric from four sides, a housing having a chamber therein, hydraulic medium within said chamber, a hydraulically operated pressure gauge communicating with said chamber, four cylinders projecting from said 30 housing toward said levers, pistons movable in said cylinders, resilient means separating said chamber of the housing from said cylinders, and means connecting said pistons to said four levers 35 for transmitting movement of said levers caused by a change in characteristic of the fabric to said pistons to thereby cause a change in the pressure condition of said hydraulic medium.

7. A device for studying the shrinkage of fabric, comprising four pivotally mounted levers having 40 means in connection therewith constructed and positioned to support fabric from four sides, a pair of rods at right angles to one another each having one end connected to one of said levers and having the free end extending to the opposed 45 lever, and gauges carried by the latter levers and operable by said rods in response to a change in characteristic of the fabric.

8. A device for studying the characteristics of fabric, comprising opposed pivotally mounted levers, means for supporting fabric between said levers, hydraulically actuated means responsive to movement of the levers as a result of change of characteristic of said fabric for indicating resistability of the fabric to lateral pressure when 55 said fabric has been subjected to shrinkage, and mechanically actuated means associated with said levers for indicating lineal dimensional changes in said fabric as the result of shrinkage.

60 ARNO PAUL NONWEILER.
